UNITED STATES PATENT OFFICE.

DAVID B. HOFFMAN, OF BALTIMORE, MARYLAND.

TOY GUN.

No. 838,330.

Specification of Letters Patent.

Patented Dec. 11, 1906.

Application filed February 19, 1906. Serial No. 301,784.

To all whom it may concern:

Be it known that I, DAVID B. HOFFMAN, of the city of Baltimore and State of Maryland, have invented certain Improvements in Toy Guns, of which the following is a specification.

This invention relates to certain improvements in that class of toy guns in which a projectile, preferably a small rod, is propelled through a tube or barrel by means of an elastic strap.

In the further description of the said invention which follows reference is made to the accompanying drawings, forming a part thereof, and in which—

Figure 1 is a partly-sectional top view of the improved toy gun, and Fig. 2 an exterior side view of the same.

Referring now to the drawings, 1 is a tube which serves as the barrel of the gun, and 2 the projectile, which in the present case consists of a plain rod. This rod is made considerably smaller in diameter than the barrel in order to reduce friction between the rod and barrel as the projectile is discharged. The means for discharging the projectile consists of an elastic strap 3, preferably india-rubber, the ends of which are attached directly to the rear end of the bar-

rel. To simplify the manner of attachment of the rubber strap, the wall of the barrel at diametrically opposite points is partially stamped out and the tongues *a* turned back against the outer surface of the barrel, as shown particularly in Fig. 1. By this construction smooth rounded surfaces *b* are produced, over which the ends of the strap are placed. The folded ends of the strap are secured by cement, which is introduced at *c*.

In the drawings the gun is shown as it appears before the rod 2 is drawn back to stretch the elastic strap. To effect this operation, the rod is grasped by the fingers after the manner of arrows used in archery.

I claim as my invention—

In a toy gun, a barrel having at one end thereof openings in its wall formed by punching out a tongue which tongues are turned back or folded over the barrel *b*, combined with a rubber strap the ends of which are inserted through the said openings and folded over the tongues and secured, substantially as specified.

DAVID B. HOFFMAN.
